INTAKE MANIFOLD SYSTEM FOR INTERNAL
COMBUSTION ENGINES

Otis C. Funderburk, Weston, Mass.

Continuation of application Serial No. 698,761,
November 20, 1933. This application July 13,
1936, Serial No. 90,362

13 Claims. (Cl. 123—52)

This invention relates to a manifold system for internal combustion engines, particularly of the type in which there are two or more, i. e., multiple banks of cylinders, and is a continuation of my copending application, Serial Number 5 698,761, filed November 20, 1933.

In this sort of engine it is common to employ as many intake manifolds as there are banks of cylinders. Each manifold is fed by a carburetor 10 and feeds the combustible mixture to one bank of cylinders to which its main chamber is usually adjacent. It is desirable to provide separate carbureting and manifolding systems in these engines because of their high rotative speeds 15 which necessitate maintaining the intake valves or ports open for a substantially longer period than that of the suction stroke of the piston. In many such multi-cylinder engines, it is necessary in order to get a full weight of charge into the cylinders to begin to open the intake valves or ports before top dead center and to keep them open for a considerable period after bottom dead center. The intake valves or ports of two or 20 even three or more cylinders are open at the same time depending on the number of cylinders in the engine.

When all of the cylinders of such an engine are fed from a single intake manifold, a cylinder in which the piston is moving most rapidly, 30 as during the middle of its suction stroke, is drawing the mixture from the manifold more powerfully than a cylinder in which the piston is moving comparatively slowly at an end of its suction stroke. The result is that each cylinder, when exerting its most powerful suction, 35 robs the other cylinders, which are then exerting a less effective suction, of some of the combustible mixture. The cylinders hence fail to receive the weight of charge which they should receive. 40 This causes loss in volumetric efficiency and hence in power.

It has been customary to use separate carbureting and manifolding systems in engines having two or more banks of cylinders, each 45 bank being served by one such system.

Difficulties in manifolding have been encountered in engines of this sort having firing orders by which some of the cylinders of one bank suck successively. For example, in an 8-cylinder 50 engine of the V type equipped with a 90° crank shaft, a firing order imposed by conditions of optimum running is 1, 5, 4, 3, 7, 2, 6, 8, etc., the cylinders of one bank being numbered 1 to 4 and the cylinders of the other bank 5 to 8. 55 With the usual arrangement of feeding each

bank of cylinders from an adjacent manifold, there are successive suctions from the same manifold and consequently there is the loss in volumetric efficiency and power as above described.

My invention overcomes this difficulty and at 5 the same time provides short and direct conduits from the manifolds to the cylinders whereby the combustible mixture is easily drawn into the cylinders and high volumetric efficiency is obtained.

In the drawings is shown an example of my invention applied to an 8-cylinder V engine assumed to have the firing order 1, 5, 4, 3, 7, 2, 1.

Fig. 1 is a plan view partly in section. 15

Fig. 2 is an elevation on the line 2—2, Fig. 1.

Fig. 3 is an elevation on the line 3—3, Fig. 1.

Fig. 4 is an elevation on the line 4—4, Fig. 1.

Fig. 5 is an elevation on the line 5—5, Fig. 1.

Fig. 6 is a diagrammatic view of the two banks 20 comprising the 8-cylinders of the engine to which my invention is applied.

I provide two intake manifolds A and B which are functionally separate from one another, each fed by an intake pipe C from a carburetor. 25 These two manifolds are preferably made together from stampings from which there are bottom members D and D' and a top member E suitably secured together by folding the peripheral edge of member D forming a lock seam 30 retaining members D, D' and E in fixed relation.

Member D' is made of a substantially uniplanar section while member D is formed with a flat peripheral flange H and a raised area having longitudinally downwardly inclined converging wall sections and formed with a concave transverse portion having its maximum curvature toward the central portion of the plate D as particularly shown in Figures 2 and 3. Member 35 E is also formed with a flat peripheral edge I and a dome like central portion on which are suitably supported the pipes C. A longitudinally vertical partition F located between pipes C and C' divides the space enclosed by stamping members E and D into two manifold chambers. The vertical partition F, as shown in Figure 5, is pro-

vided with openings formed to receive one end of pipes b which interconnect partition F with openings formed on the plate member D', these pipes passing through openings formed in the 40 flange portion H of member D. Members D and D' are also formed with co-incidently spaced openings to which are fixedly secured the short conduits a. The carburetor system is preferably 45

of the downdraft type and the pipe C from the 50 flange portion H of member D. Members D and D' are also formed with co-incidently spaced openings to which are fixedly secured the short conduits a. The carburetor system is preferably 55

carburetor leads the mixture downward and adjacent to the bottom of the chamber which preferably may consist at that place of a concave plate portion G of member D heated by exhaust gases or otherwise, the exhaust gases being conveyed and passing through the openings formed on the base plate D' to the space formed between plate D' and the raised area of the intermediate member D as particularly shown in Figure 3.

The cylinders of one bank are numbered 1, 2, 3, 4 and the cylinders of the other bank are numbered 5, 6, 7 and 8. Cylinders 1 and 4 are connected by pipes a, a, to the adjacent manifold chamber A and cylinders 5 and 8 are likewise connected to adjacent manifold chamber B. Cylinders 2 and 3 are connected by pipes b, b, shown as passing through the adjacent manifold chamber A, to the manifold chamber B on the other side of the central partition and cylinders 6 and 7 are likewise connected to chamber A. All of the pipes or conduits are short and direct and offer but little resistance to the free flow of the mixture to the cylinders whereby volumetric efficiency is not impaired.

By these means the cylinders having the firing order 1, 5, 4, 8, 6, 3, 7, 2, 1 successively draw the mixture alternately from the two intake manifold chambers. My invention, however, is not limited to V engines or to engines having this particular firing order but may be adapted to any engine having multiple banks of cylinders and a firing order in which, in order that successively firing cylinders may draw alternately from separate manifolds, each manifold feeds some of the cylinders of separate banks.

Having described my invention what I desire to secure by Letters Patent is:—

1. Manifold means adapted for use in internal combustion engines including a dome like cover of sheet metal having a flat peripheral flange; a sheet metal element having a flat section engaging the peripheral flange of said cover forming a closed compartment; a vertically disposed member dividing the compartment formed between the dome like cover and said element into two manifolding chambers; the flat sections of said cover and element formed with aligned openings; the vertically disposed member formed with openings therein; conduit means interconnecting the openings of the vertically disposed member with the openings of the cover and element; and tubular members secured to the dome like cover providing means to connect carbureting means to the manifolds.

2. Manifold means adapted for use in internal combustion engines including a dome like cover having a flat peripheral flange; a sheet metal element having a flat section engaging the peripheral flange of said cover and having a raised portion formed having longitudinally inclined downwardly converging wall sections; a vertically disposed member dividing the compartment formed between the dome like cover and said element into two manifolding chambers; the flat sections of said cover and element formed with aligned openings; the vertically disposed member formed with openings therein; conduit means interconnecting the openings of the vertically disposed member with the openings of the cover and element; and tubular members secured to the dome like cover providing means to connect the carburetor means to the manifolds.

3. Manifold means adapted for use in internal combustion engines including a sheet metal base

plate; a dome like cover having a flat peripheral flange; an intermediate sheet metal member formed with a flat edge portion and having a central raised portion; means for locking the base plate, dome like cover and intermediate member together by their peripheral edges forming thereby two closed compartments; a vertically disposed member dividing the compartment formed between the dome like member and the intermediate member into two manifolding chambers; the base plate provided with openings; the vertically disposed member provided with openings; conduit means interconnecting the openings formed on the base plate and the openings formed on the vertically disposed member; and conduits secured to the dome like cover providing means to connect carbureting means to the manifolds.

4. Manifolding means adapted for use in internal combustion engines comprising a sheet metal base plate; a sheet metal dome like cover; a sheet metal member positioned between the base plate and dome like cover dividing the space between the base plate and the dome like cover into two separate passage ways; said base plate having openings formed therein acting as conduit means from each of said passage ways; and said dome like cover having openings formed therein for connecting carbureting means to one of said passage ways.

5. Manifold means adapted for use in internal combustion engines including a substantially flat sheet metal base plate; a dome like cover having a flat peripheral flange; an intermediate sheet metal member formed with a flat edge portion and a raised central portion; the edge of the base plate being formed to hold and lock to the base plate the peripheral flange of the cover and the edge of the intermediate member forming two independent passage-ways; the base plate being provided with openings for each of said passage-ways; and the dome like cover being provided with openings providing means to connect carbureting means to one of said passage-ways.

6. Manifold means adapted for use in internal combustion engines including a substantially flat sheet metal base plate; a dome like cover having a flat peripheral flange; an intermediate sheet metal member formed with a flat edge portion and a raised central portion; the edge of the base plate being formed to hold and lock with the base plate the peripheral flange of the cover and the edge of the intermediate member forming two independent passage-ways, the base plate being provided with openings for each of said passage-ways; a vertically disposed member dividing the passage-way formed between the dome like cover and the intermediate member into two independent manifolding chambers; and the dome like cover being provided with openings for providing means to connect carbureting means to each of said manifolding chambers.

7. Manifold means adapted for use in internal combustion engines including a substantially flat sheet metal base plate; a dome like cover having a flat peripheral flange; an intermediate sheet metal member formed with a flat edge portion and a raised portion having longitudinally inclined downwardly converging wall sections toward the center of said member; the edge of the base plate being folded to hold and lock to the base plate the peripheral flange of the cover and the edge of the intermediate member forming two independent passage-ways; the base plate being provided with openings for each of said passage-ways; and the dome like cover being provided

with openings providing means to connect carbureting means to one of said passage-ways.

8. Manifold means adapted for use in internal combustion engines including a substantially flat sheet metal base plate; a dome like cover having a flat peripheral flange; an intermediate sheet metal member formed with a flat edge portion and a raised central portion; the edge of the base plate being formed to hold and lock with the base plate the peripheral flange of the cover and the edge of the intermediate member forming two independent passage-ways; a vertically disposed member dividing the passage-way formed between the dome like cover and the intermediate member into two independent manifolding chambers, said vertically disposed member being provided with spaced openings; the base plate being provided with openings for each of said passage-ways; conduit means connecting some of the openings of the base plate for one of said passage-ways with the openings of said vertically disposed member; and the dome like cover being provided with openings for providing means to connect carbureting means to each of said manifolding chambers.

9. A pressed sheet metal manifold including a plate having openings through which fuel may be delivered to cylinder intake ports, a second plate secured to the first-mentioned plate with its marginal portions lying flush against the surface of the first mentioned plate, said second mentioned plate having a portion pressed outwardly away from the first mentioned plate to provide a fuel receiving chamber between the plates, and a sheet metal partition fixed in said chamber and dividing the same into a plurality of passages.

10. A pressed sheet metal manifold including a base plate, an intermediate plate and a cover plate secured together with the marginal portions of the intermediate plate lying flush against the surfaces of the base and cover plates, said base and intermediate plates being provided with openings through which fuel may be delivered to cylinder intake ports and said intermediate plate being provided with a portion pressed outwardly away from the base plate to form a chamber adapted to receive a heating medium, said cover plate having an outwardly pressed portion enclosing and spaced from the outwardly pressed

portion of the intermediate plate to provide a fuel receiving chamber, and means disposed between the outwardly pressed portions of the intermediate and cover plates dividing the interior of the fuel receiving chamber into a plurality of 5 passages.

11. A pressed sheet metal manifold comprising a base plate having openings through which fuel may be delivered to cylinder intake ports, a second plate secured to the base plate and having 10 openings registering with the openings in the base plate, the major portion of the second plate lying flush against the upper surface of the base plate but said second plate having an upwardly pressed portion cooperating with the base plate 15 to form a chamber adapted to receive a heating medium, a cover plate having portions lying flush against said second plate and having an upwardly pressed portion enclosing and spaced from the upwardly pressed portion of said second plate to 20 provide a fuel receiving chamber, said cover plate being secured to the base plate, and a sheet metal partition between the raised portion of the second plate and the raised portion of the cover plate dividing the interior of the fuel receiving 25 chamber into a plurality of passages.

12. A pressed sheet metal manifold including a plate having openings through which fuel may be delivered to cylinder intake ports, a second plate secured to the first mentioned plate with its marginal portions lying flush against the surface of the first-mentioned plate, one of said plates having a portion pressed outwardly away from the other plate to provide fuel conducting passages 30 communicating with the said openings, and means for supplying an explosive mixture to said fuel conducting passages.

13. A pressed sheet metal manifold including a plate having openings through which fuel may be delivered to cylinder intake ports, a second plate 40 secured to the first-mentioned plate with its marginal portions lying flush against the surface of the first mentioned plate, one of said plates having a portion pressed outwardly away from the other plate to provide a fuel receiving chamber, 45 and means disposed in the said chamber dividing the interior thereof into a plurality of passages.

OTIS C. FUNDERBURK.
